SURFACE EFFECT SHIP

Scott C. Rethorst, 1661 Lombardy Road, Pasadena, Calif.

Filed Mar. 25, 1963, Ser. No. 74,125

Term of patent 14 years

(Cl. D71—1)

FIG. 1

FIG. 2

FIG. 3

FIG. 4

FIGURE 1 is a top plan view of a surface effect ship showing my new design;

FIGURE 2 is a side elevational view thereof;

FIGURE 3 is a front elevational view thereof; and

FIG. 4 is a rear elevational view thereof.

The essential features of my design reside in the convex raised central ridge below the cockpit in combination with the supporting hull comprised of the outer elongated pontoon-like hulls and the flat bottom therebetween.

I claim:

The ornamental design for a surface effect ship, as shown and described.
